UNITED STATES PATENT OFFICE.

CHARLES PRIESTLEY, OF BRADFORD, COUNTY OF YORK, ENGLAND.

MAKING-UP BOARD FOR PIECE GOODS.

SPECIFICATION forming part of Letters Patent No. 340,521, dated April 20, 1886.

Application filed September 14, 1885. Serial No. 177,130. (No model.) Patented in England June 8, 1885, No. 6,911.

To all whom it may concern:

Be it known that I, CHARLES PRIESTLEY, a subject of the Queen of Great Britain and Ireland, and residing at Bradford, in the county of York, England, have invented certain Improvements in Making-Up Boards for Piece Goods, (for which I have obtained Letters Patent in Great Britain numbered 6,911, dated 8th day of June, 1885,) of which the following is a specification.

The object of this invention is to protect the piece which is wrapped around the board from marking or other injury to the same incidental to sap or other natural ingredients of the wood passing into the piece.

Formerly I covered the board with material having a seam or joint; but while this cover protected the piece from being marked in any way by the wood of the board the seam or joining marked the piece.

Figure 1 is a perspective view of my making-up board. Fig. 2 is a cross-section of the same at the line X X of Fig. 1.

Similar letters refer to similar parts throughout the several views.

My invention consists in covering the making-up board B with a seamless cover, A, as a protection to the piece wound around the same, not only from the wood of the board, but from the marking of the piece by the use of a cover with a seam or joint.

The seamless cover A may be made in the same way as seamless rice or sugar bags are made, and of every suitable material.

What I claim is—

A making-up board provided with a seamless cover, substantially as described.

In testimony whereof I have signed my name to this specification in the presence of two subscribing witnesses.

CHARLES PRIESTLEY.

Witnesses:

JOHN WAUGH,
RD. B. NICHOLLS.
